DESIGN FOR A TELEPHONE HAND SET

Louis Kniep, Jr., East Orange, N. J., assignor to
Federal Telephone and Radio Corporation, New
York, N. Y., a corporation of Delaware

Application March 24, 1947, Serial No. 137,830

Term of patent 14 years

(Cl. D26—14)

To all whom it may concern:

Be it known that I, Louis Kniep, Jr., a citizen of the United States, residing at 136A South Munn Avenue, East Orange, New Jersey, have invented a new, original, and ornamental Design for a Telephone Hand Set, of which the following is a specification, reference being had to the accompanying drawing, forming part thereof.

Fig. 1 is a top plan view of the telephone hand set showing my new design;

Fig. 2 is a view in side elevation of the hand set;

Fig. 3 is a view taken from line 3—3 of Fig. 2 showing the transmitter end of the hand set; and

Fig. 4 is a view taken from line 4—4 of Fig. 2 showing the receiver end of the hand set.

I claim:

The ornamental design for a telephone hand set, substantially as shown.

LOUIS KNIEP, JR.
